UNITED STATES PATENT OFFICE

112,197

DESIGN FOR A HAIR CURLER

Frances M. Jones, Burlington, Iowa

Application August 16, 1937, Serial No. 71,122

Term of patent 7 years

To all whom it may concern:

Be it known that I, Frances M. Jones, a citizen of the United States and a resident of the city of Burlington, in the county of Des Moines and State of Iowa, have invented a new, original, and ornamental Design for a Hair Curler, of which the following is the specification, and reference being had to the accompanying drawing, forming a part thereof.

Fig. 1 is a perspective view of a hair curler showing my new design.

Fig. 2 is a top plan view; and,

Fig. 3 is a side elevational view thereof.

I claim:

The ornamental design for a hair curler, as shown.

FRANCES M. JONES,
